FLASK STRIPPER

Peer D. Nielsen, Lorain, Ohio, assignor to National Tube Company, a corporation of New Jersey

Application January 15, 1941, Serial No. 374,554

2 Claims. (Cl. 22—95)

This invention relates to a device peculiarly well suited to facilitate the removal of an ingot mold casting from the flask section of the mold in which the ingot mold was cast.

After an ingot mold is poured and allowed to cool for a suitable period of time, the top and bottom pouring plates are removed, the core arbor extracted, and the remainder of the assembly, with the mold casting therein, is tipped on its side with the flanges, by means of which the two halves of the flask are bolted together, disposed approximately in a horizontal plane. The bolts in the flanges of the flask sections are then removed and the top half of the flask lifted off by means of a crane, hoist or other suitable lifting apparatus. The flask section has a very pronounced tendency to adhere to the ingot mold casting. However, the top section is readily lifted off as the combined weight of the ingot mold, sand, and lower section of the flask is sufficient to break the bond between the sand and the upper half of the flask as it is lifted by the crane hoist.

To remove the lower section of the flask the usual practice is to engage the ingot mold casting, with hooks suspended from the crane hoist, lift it and the lower flask section slightly above floor level, and then repeatedly apply sledge hammer blows to the flange of the lower flask section until it drops away from the ingot mold casting and thus completes the separation of the parts.

Sledging is required to remove the lower section of the flask, as the weight of this section, when the ingot mold casting is suspended from the crane, is insufficient to break the bond between the flask section and the sand.

At the time the above separating operation is performed, the ingot mold casting is still red hot and the flask assembly is at a high temperature. The sledging operation often requires the services of several men before removal of the lower flask section is effected, and is a particularly arduous task on account of the physical effort involved in the sledging and the extreme heat to which the workmen are subjected.

Sledging has been resorted to in the past in preference to rolling the assembly over to dispose the remaining half flask section on top of the ingot mold casting, where it could be removed in the same way that the other flask section was removed. The reason this practice has been followed is that the rolling operation requires more floor space than is sometimes avail-

able and the time required is so great that it is less economical than the sledging operation.

The present invention aims to eliminate the costly and arduous manual labor required to free the lower section of flask from the ingot mold casting, to accomplish this result without increasing floor space requirements, and to enable the foundry to perform the work in less time than heretofore required.

10 The invention also aims to provide a stripping device so constructed and arranged that it will translate the weight of the object being stripped into the force required to effect the stripping.

15 A further aim is to provide a lever system which, by means of the mechanical advantage incorporated therein, translates the weight of the mold, sand, and flask section into a force sufficient to break the flask section free, and to provide means to apply this developed force in a manner to effect stripping.

20 The above and other features of the invention which are defined with particularity in the appended claims, will be fully understood from the following detailed disclosure when read in connection with the accompanying drawings, in which:

25 Figure 1 is a side elevation of the improved stripping device shown in the act of engaging an ingot mold casting and the lower flask section at the beginning of the stripping stroke.

30 Figure 2 is an end elevation of a part shown in Figure 1, with the ingot mold and lower flask section shown in section.

35 Figure 3 is a side elevation of the stripping device shown in the position which it assumes at the end of the stripping stroke.

Figure 4 is a fragmentary end view projected from Figure 3.

40 Figure 5 is an end elevation with parts shown in section as in Figure 2, but showing the parts of the stripping device in the positions they assume at the completion of the stripping stroke.

45 Referring in detail to the drawings, the stripping device consists of a rigid yoke 1 constructed to span the ingot mold casting when feet 2 of the yoke rest upon the upper flanged face of the lower flask section containing the casting. Pins 3 are positioned in the yoke 1 to limit the travel of a movable yoke-like frame 4 by projecting 50 into slots 5 in yoke 1. The yoke 4 is moved in relation to yoke 1 by means of levers 6 which rock about fulcrums 7 and act through rollers 8 upon the flat upper surfaces 9 of yoke 1. The levers 7 are connected through links 10 to a ring 55 11 by means of which the stripping device is sus-

pended from the hook of a suitable hoist carried by an overhead crane. A hook 12 having a jaw 13 is movably engaged by means of pin 14 to clevis 15 which is securely bolted to the movable yoke 4.

In operation the stripping device is suspended from a crane hoist and is disposed on the lower flask section and casting as shown in Figure 1, the jaw 13 of hook 12 being entered into the open end of the casting and feet 2 of yoke 1 resting on the flanges of the lower flask section. When the crane raises ring 11 the frame 4 and yoke 1 are moved apart by the force developed from the weight of the assembly reacting through the lever system. The mechanical advantage of the lever system and the distance through which it is permitted to act develops sufficient power and movement to free the casting from the flask section.

A particular advantage of this stripping device is that no outside source of power is required to develop the force necessary to effect stripping. The load on the crane, from which the device is suspended, is entirely independent from the stripping force developed, being merely the weight of the stripper and the ingot mold casting, sand, and flask section lifted.

While I have described quite precisely the details of a specific embodiment of the invention herein illustrated, it is to be understood that the drawings and description are to be interpreted in an illustrative rather than a limiting sense, since various modifications may be made without departure from the invention as defined in the appended claims.

I claim:

1. A device for stripping a casting from a flask

section of the mold in which it was cast consisting of a yoke including mold engaging legs connected by a body portion adapted to straddle the mold, a frame connected to the body portion of the yoke with freedom for limited movement relative thereto, a pair of levers pivoted to said frame and arranged to react against said yoke, a suspension member adapted to be supported from an overhead hoist, respective links connecting said levers with said suspension member, and a casting-engaging element depending from said frame at a point between said legs.

2. A device for stripping a casting from a flask section of the mold in which it was cast, consisting of an inverted U-shaped yoke having mold engaging legs connected by a body portion adapted to straddle the mold, a frame having a pin and slot connection with the body portion of the yoke so as to permit of limited relative movement between the frame and the yoke, a pair of levers pivoted symmetrically on opposite sides of the median portion of said frame, said yoke having flat surfaces on its upper extremity at locations circularly spaced on opposite sides of the vertical median axis thereof, said levers carrying respective rollers adapted to engage the said surfaces on the yoke, a suspension member adapted to be supported from an overhead hoist, links pivoted respectively to the suspension members and to said levers, and a casting engaging element pivotally suspended from said frame and having a hooked portion formed on its lower extremity adapted to enter the cavity in a casting to be stripped from the mold.
